Charles W. Beamer

By Clarence O'Brien.

Attorney

UNITED STATES PATENT OFFICE.

CHARLES W. BEAMER, OF TONOPAH, NEVADA.

COMBINATION BRACE AND DRILL.

Application filed June 9, 1926. Serial No. 114,734.

This invention relates to an improved tool, and it has more specific reference to an improved structure including a brace, and an improved drill attachment therefor.

5 Briefly, the brace is of conventional design with the exception of a socket which is formed in the inner end of the chuck. The drill brace attachment, however, is modified to make a substantially improved one 10 which may be used in the form of an attachment to be applied to or removed from the brace as conditions require. A special clamp and coupling is simply provided for connecting the shaft of the drill brace attachment 15 to a part of the brace, and the driving pinion is modified to afford a driving connection with the improved brace chuck.

20 My principal aim is to provide a combination device of this kind to make for convenience and compactness and to afford the use of the well known convenient breast support of the brace for producing a firm and efficient support for the drill.

25 Other objects and advantages of the invention will become apparent from the following description and drawing.

In the drawing:

Figure 1 is a view which is mainly in full elevation, with portions of the parts broken 30 away and shown in section to disclose the construction clearly.

Figure 2 is a section taken approximately upon the plane of the line 2-2 of Figure 1 looking in the direction of the arrows, and 35

Figure 3 is also a section taken upon the plane of the line 3-3 of Figure 1, looking in the direction of the arrow.

Referring to the drawing in detail, the reference character 1 designates generally 40 the brace, and the reference character 2 the improved drill brace attachment for said brace.

The brace embodies the usual breast rest or plate 3, a U-shaped portion 4, a hand grip 5, pawl and ratchet mechanism 6, knurled bushing 7, and customary tool chuck 8. As before stated, the only real change in the make up of the brace is the provision 50 of a polygonal socket in the inner end of the chuck. It might be stated in this connection, however, that a special clamp 9 is provided and this is of a two-part construction and the parts are firmly clamped about the bend in the brace adjacent the breast 55 plate 3. As indicated in dotted lines this

clamp includes a polygonal projection 10 which is formed integral therewith.

As for the drill brace attachment, this comprises a beveled gear 11, an operating crank 12, a hand grip 13, and shaft 14, 60 mounted for rotation upon the reduced end of the shaft is a beveled pinion 15 which meshes with the teeth of the beveled gear 11, and it will be noted that this pinion is provided with a polygonal extension 16 65 which fits into the square socket in the adjacent end of the chuck 8, thus providing a driving connection between the pinion and the chuck, the power being received from the beveled gear. The reference character 70 17 designates a sleeve, having a square socket formed in its outer end as shown at 18^a in Figure 3. Obviously, this socket serves to receive the aforesaid correspondingly shaped extension 10. In the opposite end of the 75 sleeve one end of the shaft 14 is fitted for rotation. As shown plainly in Figure 1 in dotted lines at 18, a set screw is carried by the sleeve 17 and fits into a recess formed in the telescoping end of the shaft 14. Then 80 too, a coiled spring 19 surrounds this portion of the shaft, bearing at one end against the sleeve and at its opposite end against an appropriate shoulder on the shaft. I 85 would direct attention to the fact that the set screw and groove connection 18 is such as to permit sliding of the sleeve in a direction from right to left against the tension of the spring 19 to permit separation of this 90 novel coupling.

It is obvious that when it is desired to bring the drill 2 into play, it is associated with the brace as shown plainly in Figure 1. In doing this it is only necessary to seat the extension 16 in the square socket formed 95 in the chuck 8. Then the sleeve 17, which is milled on its exterior is grapsed and moved in a direction from right to left against the tension of the spring, permitting the opposite socket carrying end to be 100 snapped onto the aforesaid extension 10 on the clamp 9. This holds the drill in place in the U-shaped portion of the brace. Obviously, then it is operated in the usual way 105 through the medium of the crank while using the brace as a firm support for it.

The advantage of this combination of parts will be plainly obvious to those skilled in the art to which the invention relates. Moreover, the specific construction will be 110

clear, as will be the operation and application and also removal. It is therefore believed that a more specific and detailed description is unnecessary.

5 While I have shown and described the preferred embodiment of the invention it is to be understood that minor changes coming within the field of invention claimed may be resorted to if desired.

10 Having thus described the invention, what I claim as new and desire to secure by Letters Patent is:—

15 1. In a tool of the class described, in combination, a brace including the usual U-shaped portion, pawl and ratchet mechanism, bushing, and chuck rotatably mounted in the bushing, said chuck being provided at its inner end with a polygonal socket, a clamp carried by a remote arm of the U-shaped portion of the brace, said clamp being provided with a polygonal extension, a drill attachment for the brace including a beveled gear, a shaft provided with means for mounting said gear to rotate in a plane substantially parallel to said shaft, a pinion rotatably mounted on one end of the shaft

and meshing with the gear, said pinion being provided with an extension fitting into the aforesaid socket, a spring pressed coupling sleeve mounted upon the opposite end 30 of the shaft and provided with a polygonal socket for reception of the correspondingly shaped extension on said clamp.

2. In a tool of the class described, in combination, a brace including the usual U- 35 shaped portion, pawl and ratchet mechanism, bushing, and chuck rotatably mounted in the bushing, said chuck being provided at its inner end with a socket, a drill brace attachment including a bevelled gear, a shaft 40 provided with means, for mounting said gear to rotate in a plane substantially parallel to said shaft, a pinion rotatably mounted on one end of the shaft and meshing with the gear, said pinion being provided with an 45 extension fitting into the aforesaid socket and a quick detachable coupling at the opposite end of the shaft and the adjacent arm of said brace.

In testimony whereof I affix my signature,

CHARLES W. BEAMER.
